UNITED STATES PATENT OFFICE

CHARLES W. MORGAN, OF CHICAGO, ILLINOIS

DESIGN FOR A GAME BOARD

Application filed May 29, 1929. Serial No. 31,450. Term of patent 7 years.

To all whom it may concern:

Be it known that I, CHARLES W. MORGAN, a citizen of the United States, residing at Chicago, in the county of Cook and State of Illinois, have invented a new, original, and ornamental Design for Game Board, of which the following is a specification, reference being had to the accompanying drawing, forming part thereof.

The figure is a plan view of a game board, showing my new design.

I claim:

The ornamental design for a game board, substantially as shown.

CHARLES W. MORGAN.
